UNITED STATES PATENT OFFICE.

MARTIN HERZ, OF BROOKLYN, NEW YORK.

CHAIR-SEAT.

SPECIFICATION forming part of Letters Patent No. 442,581, dated December 9, 1890.

Application filed March 6, 1890. Serial No. 343,080. (No model.)

To all whom it may concern:

Be it known that I, MARTIN HERZ, a citizen of the United States, residing at Brooklyn, in the county of Kings and State of New York, 5 have invented certain new and useful Improvements in Chair-Seats; and I do declare the following to be a full, clear, and exact description of the invention, such as will enable others skilled in the art to which it app-
10 pertains to make and use the same.

My invention relates to seats for chairs, chair-backs, &c.; and it consists in the improved construction and ornamentation of such a seat and in the method of producing 15 the same, as will be hereinafter more particularly set forth.

Referring to the accompanying drawings, Figure 1 is a plan view of a chair-seat embodying my invention, and Fig. 2 is a vertical 20 sectional view of the same enlarged.

In the manufacture of the ordinary veneer seats in which the grain of the central or middle piece of veneer is placed at right angles to the top and bottom pieces it is often de-
25 sirable to ornament the upper layer in imitation of leather or other material. To accom-
plish this quickly and cheaply, I first form the seat 1 in the usual manner by gluing the three pieces together, and after the glue has
30 dried I apply an oil-stain to one side and let it set for a few minutes, when I pass it through embossing-rollers, one of which is provided with a pattern or design of any kind cut or engraved upon its surface, which will thus
35 compress the seat, except the portions 2, which come under the engraved or cut-out portions of the roller, which will be thus left in its normal condition. I have found by experience that this raised portion of the design or fig-
40 ure which is left in its normal condition re-
tains a much darker color than the depressed portion or background, as it were, and without attempting a full explanation of the causes of these contrasting colors, produced
45 by the application of pressure upon stock con-
taining but one coloring-matter, it is natural to presume that that portion or portions of the stock which come under the cut-out parts of the figure on the die or roller receiving
50 less compression, its fibers remain less com-

pact or condensed than the depressed portions, and consequently take up more of the coloring-matter, while the depressed portions which have the fibers condensed also have the coloring-matter thinned out or spread as 55 it is pressed into the wood. Again, the glue on the intermediate veneer may serve to prevent the coloring-matter from going beyond the first layer or veneer, and thereby retain it in the manner described. 6c

The seat may be made out of only one thickness, and can then be varnished or otherwise treated, when it will be ready for use.

By my improved process, as above set forth, the design or raised portion will be caused to 65 stand out in relief and produce a most beau-
tiful effect—as, for instance, it can be made to imitate leather with a pattern formed in the middle.

As the fiber or grain of the wood is not in-
jured by treating it as above described, the upper piece of the seat is made to perform 70 the double duty of strengthening the seat and forming a raised pattern for the reception of the coloring material, which only affects 75 the outer surface of such raised portion.

One of the rollers is plain and the other one is provided with the pattern or design, and they can be used hot or cold; but as they form no part of this invention I have not 80 shown them. By passing the wood between the calender-rolls I can emboss it and pro-
duce a very desirable article; but the design will hardly be noticeable until it is colored, when the shading thus effected will produce 85 the desired result.

While I have described my process as being applied to the ornamentation of chair-seats made of wood, yet it is obvious that the same might be used on paper or other fibrous 90 material, and that chair-backs and various other articles may be treated in the same manner without departing from the spirit of my invention.

Having described my invention, what I 95 claim is—

1. The within-described process of emboss-
ing and coloring wood, consisting in applying a coating of oil-stain to the surface to be op-
erated upon, and after it has set subjecting 100

the same to and producing a design or pattern thereon by pressure, substantially as specified.

2. The process of producing chair-seats, consisting, first, in uniting two or more veneers of material with their grain crossing each other; second, applying a stain to the top layer, and, finally, subjecting the united layers to and producing a design or pattern thereon by pressure, so as to imitate embossed leather and produce shading in contrasting colors, substantially as specified.

3. A chair-seat of stained embossed wood the raised pattern of which appears of a different shade or tint from the body or ground, substantially as specified. 15

In testimony whereof I affix my signature in presence of two witnesses.

MARTIN HERZ.
